UNITED STATES PATENT OFFICE

129,006

DESIGN FOR AN ATOMIZER

Walter Schwarz, La Crescenta, Calif., assignor to
Standard Homeopathic Company, a corpora-
tion of Nevada

Application March 7, 1941, Serial No. 99,416

Term of patent 7 years

To all whom it may concern:

Be it known that I, Walter Schwarz, a citizen of the United States, residing at La Crescenta, in the county of Los Angeles, State of California, having invented a new, original, and ornamental Design for an Atomizer, of which the following is a specification, reference being had to the accompanying drawing, forming part thereof.

In the drawing—

Fig. 1 is a side elevational view of an atomizer embodying my new design;

Fig. 2 is a fragmentary front elevational view of

the article shown in Fig. 1, but with the connecting tube and bulb omitted; and

Fig. 3 is a top plan view of the spray head portion shown in Fig. 1, with the connecting tube and bulb omitted.

The essential features of my design are shown in full lines.

I claim:

The ornamental design for an atomizer, substantially as shown and described.

WALTER SCHWARZ.
